COIN MACHINE

Karl Gammel, Joliet, Ill.

Application August 7, 1933, Serial No. 684,037

10 Claims. (Cl. 194—55)

The invention relates to coin controlled machines, and more particularly to such machines wherein the coin is tested to prevent the use of improper coins, slugs, washers and the like.

5 The invention further relates to a machine which has a broad field of utility and which, while comparatively simple in operation, is capable of such accurate adjustment that only the proper coin or token can be used to operate the machine.

10 The invention also provides means for producing a warning signal in the event that an attempt is made to cause the machine to operate through the use of coins or tokens for which the machine is not adjusted.

15 In accordance with the invention, a contact member cooperates with a coin carrying member to prevent operation of the machine when an improper coin, slug, washer, or the like is inserted in the machine.

20 The invention also consists in certain new and original features of construction and combinations of parts hereinafter set forth and claimed.

25 Although the novel features which are believed to be characteristic of this invention will be particularly pointed out in the claims appended hereto, the invention itself, as to its objects and advantages, and the manner in which it may be carried out, may be better understood 30 by referring to the following description taken in connection with the accompanying drawings forming a part thereof, in which

35 Figure 1 is a plan view of a machine constructed in accordance with the invention;

Figure 2 is a vertical longitudinal section on the line II—II of Figure 1;

Figure 3 is a vertical section similar to that shown in Figure 2, illustrating the operation of the machine;

40 Figure 4 is an elevation of the machine illustrated in Figure 1 as viewed from the left;

Figure 5 is a partial vertical section similar to that illustrated in Figure 3, illustrating the operation of the machine under different conditions;

45 Figure 6 is a plan view of a variant form of the machine;

Figure 7 is a vertical longitudinal section on the line VII—VII of Figure 6, and

50 Figure 8 is a partial vertical section corresponding to Figure 7 but showing the machine parts in a different position.

In the following description and claims various details will be identified by specific names for convenience, but they are intended to be as

generic in their application as the art will permit.

Like reference characters denote like parts in the several figures of the drawings.

In the drawings accompanying and forming 5 part of this specification, certain specific disclosures of the invention is made for purposes of explanation, but it will be understood that the details may be modified in various respects without departure from the broad aspect of the in- 10 vention.

Referring now more particularly to the drawings, it will be seen that they show a frame 10, a carrying member or coin slide 11, reciprocable in the frame 10, which may be carried in a 15 special sheath member 12 open at its upper side for insertion of a coin 13 in a suitable opening 14 in the coin slide 11.

The coin slide 11 may bear a representation 15 of the coin with which the machine is intended 20 to be used, adjacent the opening 14, as illustrated in Figure 1. The representation 15 of the coin indicates to the user of the machine the proper position or orientation of the coin when placed in the opening 14 in the coin slide. 25

An opening 16 is provided in the frame through which the coin 13 may drop when the coin-carrying member or coin slide is pushed inwardly to its extreme position in the machine. Thus if a coin is inserted in the opening 14 of the coin 30 slide, when the latter is in the position illustrated in Figure 1, and if the coin slide 11 is pushed into the machine as far as it will go, the coin 13 will drop through the opening 16 into the machine. If the coin will not pass the selecting apparatus (which will be described subsequently) the coin slide may be returned to its initial position, and a hole 17 in the sheath member 12 permits the coin to be extracted from the coin-carrying member by insertion of the finger 40 from below the sheath and pressure upon the lower face of the coin.

The selecting apparatus, which prevents successful use of improper coins, slugs, washers, and the like, comprises a toggle 18, pivoted in the frame 10 of the machine as by screws 19—19; a connecting lever 20, pivoted at 21 to the toggle 18; and a contact member 22 pivoted at 23 to the connecting lever 20. Thus, movement of the toggle 18 about the axis of the pivoting screws 45 19 will move the connecting lever 20 which is pivoted to the toggle and through it will move the contact member 22 which is pivoted to the connecting lever. Helical springs 24—24 are attached to the frame 10 at 25—25 and to the ends 50 55 of the toggle 18.

26—26 of the toggle 18 which are on the opposite side of the pivot screws 19—19 from the pivot 21 of the connecting lever 20. The springs 24—24 constitute a toggle mechanism with the toggle 5 18 and the connecting lever 20, and tend to rotate the toggle 18 about the pivot screws 19 in a clockwise direction and thus to incline the pivot 21 of the connecting lever 20 toward the point of entrance of the coin slide 11 into the frame 10. A 10 set screw 27 is disposed in the frame for contact with the end of the toggle, adjacent the pivot 21 of the connecting lever 20, in order that the movement of the toggle 18 by the helical springs 24—24 may be arrested at the desired point.

15 The connecting lever 20 comprises two legs, one leg 28 being positioned for contact with the forward end of the coin slide 11 as it is pushed into the machine and the other leg 29, being adapted for contact with the upper surface of the coin 20 slide.

Assuming, for the moment, that the contact member 22 is not included in the apparatus, it will be seen that when the coin slide 11 is pushed into the machine, its forward end will contact with the 25 leg 28 of the connecting lever 20 and turn the latter about its pivot 21 in the toggle 18. Thereupon the leg 29 nearest the coin slide will be pressed upon the face of the coin slide as illustrated in Figures 3 and 5. Further movement of the 30 coin slide into the machine will, thereupon, turn the toggle 18 about its pivot screws 19—19 and the coin slide 11 will attain its extreme innermost position in the machine with the opening 14 of the coin slide in register with the opening 16 in the frame. A coin 13 carried in the opening 14 in the coin slide may thus be inserted in the 35 machine to control its operation.

Means is provided, however, to prevent an improper coin, slug, washer, etc., from reaching the 40 opening 16. For purposes of illustration, the contact member 22 is described as constituting this means. Projections 30 and 31 are provided on the contact member adjacent the pivot 23 by means of which the latter is carried by the connecting lever 45 20. A spring 121 is provided which exerts a force against the connecting lever 20 in a counterclockwise direction about pivot 21. In this manner the lever 20 is held in open position so that the coin slide 11 may pass inwardly unobstructed until the 50 end of the slide strikes leg 28 of lever 20. Limited counterclockwise movement of lever 20 is provided by leg 28 coming in contact with the rim of hole 16 as shown in Fig. 2. A leaf spring 32 provides shock absorbing means for contact member 55 22 and prevents it from the possibility of jumping, should the slide 11 be thrust with sudden impulse.

When the leg 28 of the connecting lever 20 is engaged by the end of the coin slide 11 and the connecting lever is turned about its pivot 21, in the toggle 18, the leg 29 being depressed thereby, the contact points 30 and 31 will be brought to bear upon the upper face of the coin 13 in the coin slide 11. The angular position of the contact lever 22, 60 with respect to its pivot 23, will be determined by the elevation of two points on the upper face of the coin.

The force which the end of the coin slide 11 exerts upon the leg 28 of the connecting lever 20, 70 and which depresses the pivot 23 of the member 22 toward the coin 13, is sufficient to overcome the action of the leaf spring 32 upon the contact member as the contact points 30 and 31 bear upon the upper face of the coin 13. The free end 33 of the contact member 22 will therefore be elevated

from the position illustrated in Figure 2 as the coin slide, with a coin therein, is pushed into the machine.

A plate 34 is fixed to the frame 10 beyond the free end 33 of the contact member 22 in a plane substantially at right-angles to that of the coin slide 11. Clearly the plate 34 need not be a separate member but may be formed as a part of the frame 10 without the exercise of invention. An opening 35 is formed in the plate 34 through which the free end 33 of the contact member 22 may pass.

The location of the opening 35 in the plate 34 is such that the free end 33 of the contact member 22 will pass through it only when the contact 15 points 30 and 31 on the contact member bear upon a proper coin, properly placed in the coin slide. During the operation which has already been described, if a proper coin is not properly placed or oriented in the coin slide or if an improper coin, 20 slug, washer, etc., be placed in the coin slide, the contact points 30 and 31 will come to rest upon higher or lower surfaces than would be the case with a proper coin, properly placed. The coin slide, therefore, being pushed further into the 25 machine and acting upon the leg 28 of the contact connecting lever 20, will be unable to carry the coin or other article therein as far as the opening 16 in the frame, because the free end 33 of the contact member will be stopped by the plate 34, 30 and will not permit the contact member 22 or the connecting lever 20 or its pivot or the toggle 18, to which the connecting lever 20 is in turn pivoted, to move a sufficient distance to allow the opening 14 in the coin slide to register with the opening 16 in the frame.

From the foregoing description, it will be evident that an improper article in the opening 14 of the coin slide will not pass into the coin control part of the machine because of the selecting 40 apparatus which has been described. Only a proper coin, properly placed will cause the free end 33 of the contact member to assume the required position in which it may pass through the opening 35 in the plate 34 to permit the coin 45 to be deposited in the machine.

When the toggle 18 is turned about its pivot-screws 19, a bracket 46 thereon may contact with and activate an operating part of the machine. It may be desired to give an alarm by 50 means of a visual or an oral signal in case it is attempted to use the machine without a proper coin. To this end the plate 34 may be cut away as at 36 (see Figure 4) and a movable segment 37, with the opening 35 properly positioned 55 therein, may be loosely attached to the plate proper, as at 38, being held in position by a dowel 39 and spring 40. An electrical pole 41, with an insulated wire 42 attached thereto, may be then positioned adjacent the movable segment 37 on the side thereof opposite to that adjacent which the free end 33 of the contact member 32 is disposed. A light, bell, or other signal (not shown) may be placed in circuit with the wire 42 and the circuit may be completed 60 through a source of electromotive force to the frame of the machine where it is grounded as indicated at 43. With such an arrangement it is of course necessary to insulate the electrical pole 41 from the plate 34 and the movable segment 37 and such insulation is illustrated at 44. From the foregoing, it will be evident that if the free end 33 of the contact member 22 is forced 70 against the movable segment 37, an electrical connection will be made through the alarm mem- 75

ber and will indicate the fact that the machine is being improperly operated.

Instead of using a single contact member 22, it may be desired to substitute therefore two contact members so that operation of the machine will be dependent upon two distinct elevations on the embossed surface of the coin. Such an apparatus is illustrated in Figures 6, 7, and 8, the contact members 22a and 22b being pivoted to the connecting lever 20 in place of the single contact member 22. The contact points are illustrated as being adjustable, that of the contact member 22a being on one side of the pivot 23 and that of the contact member 22b being on the other side of the pivot. A single spring 32a serves to depress each contact point with respect to the connecting lever 20, and accordingly the free end 33b of contact member 22b normally lies below the opening 35 in the movable segment 37 of the plate 34, whereas, the free end 33a of the contact member 22a normally lies above the opening 35, its position being limited by a bracket 45, attached to the plate 34. A properly embossed coin oriented in the coin slide 11 presents a surface at the proper elevation to the contact point on each lever, the free ends 33a and 33b attaining exactly the correct elevation as the coin slide 11 is pushed in. Each free end passes through the plate permitting the coin to fall from the opening 14 in the coin slide through the opening 16 in the frame. An improper coin, slug, washer or the like on the coin slide will cause one or both free ends to strike the plate 34 and the machine will not operate.

From the foregoing description it will be seen that a coin machine is provided which is of very simple construction yet capable of such accurate adjustment as to render it practically infallible in the automatic selection of the proper coin or token to operate the machine. This invention has a wide field of utility in connection with automatic amusement and vending machines of all types, mechanical pianos and phonographs, coin telephones, automatic turnstiles and the like.

Furthermore, the invention provides for a warning signal to be manipulated by an attempted improper use of the machine. This machine is particularly adaptable for use in places where it is not feasible to have an attendant in the vicinity, such as, for example, public telephone booths or vending and amusement devices in isolated or other locations.

While certain novel features of the invention have been disclosed and are pointed out in the annexed claims, it will be understood that various omissions, substitutions and changes may be made by those skilled in the art without departing from the spirit of the invention.

What is claimed is:

1. In a coin-controlled machine, a coin-carrying member, a toggle mechanism, a contact member mounted on said toggle mechanism, a projection adjustably secured on one end of said contact member for contacting a coin in said coin-carrying member, and a plate beyond the other end of said contact member having an opening therein through which the end of said contact member may pass.

2. In a coin-controlled machine, a frame, a coin slide in said frame, a toggle pivoted in said frame, a connecting lever pivoted to said toggle, a contact member pivoted to said connecting lever for contacting a coin in said coin slide, and

means adapted to limit the inward movement of said contact member.

3. In a coin-controlled machine, a frame, a coin slide in said frame, a toggle pivoted in said frame, a connecting lever pivoted to said toggle, a contact member pivoted to said connecting lever for contacting a coin in said coin slide, in combination with a spring tending to rotate said toggle about its pivot toward the entering coin slide and a second spring tending to rotate said contact member out of contact with a coin in said coin slide, and means for limiting the movement of said contact member.

4. In a coin-controlled machine, a frame, a coin slide in said frame, a toggle pivoted in said frame, a stop member fixed to said frame, a connecting lever pivoted to said toggle, and a contact member pivoted to said connecting lever for contacting a coin in said coin slide, in combination with a projection on said contact member for contact with said coin slide as it moves the coin into the machine, said projection being constructed and arranged to depress the contact member pivot and bring the contact member against the coin, and a spring tending to hold the contact member away from the coin.

5. In a coin-controlled machine, a frame, a coin slide in said frame, a toggle pivoted in said frame, a connecting lever pivoted to said toggle, a contact member pivoted to said connecting lever for contacting a coin in said coin slide, in combination with a spring connecting one end of said toggle to said frame to depress said connecting lever toward said coin slide, and means for limiting the inward movement of said contact member.

6. In a coin-controlled machine, a coin slide, a pivoted connecting lever comprising one leg for contact with the forward end of said slide as it is pushed into the machine, a second leg adapted for contact with the upper surface of said slide when said first named leg is turned about its pivot by said slide, a contact member pivoted in said second leg, a projection on one end of said contact member for contacting a coin in said coin-carrying member, said projection being brought into contact with the coin by action of said coin slide upon said connecting lever, and stopping means adjacent the opposite end of said contact member.

7. In a coin-controlled machine, a coin-carrying member, a contact member, a projection on one end of said contact member for contacting a coin in said coin-carrying member, and a plate beyond the other end of said contact member, in combination with a movable segment in said plate having an opening therein through which the end of said contact member may pass, and an electrical connection adjacent and operable by said movable segment upon movement thereof by the end of the contact member.

8. In a coin-controlled machine, a frame, a coin slide in said frame, a toggle pivoted in said frame, a connecting lever pivoted to said toggle, a plurality of contact members pivoted to said connecting lever for contacting a coin in said coin slide in a plurality of points, and stopping means to limit the movement of said contact members.

9. In a coin-controlled machine, a coin slide, a frame in which said coin slide operates, said frame having an opening through which a coin in said coin slide may drop, a toggle pivoted in said frame, a lever system pivoted to said toggle for contact with said slide and with a proper coin

- in said slide to move said lever system and said toggle with said slide only when a proper coin is in said slide, and means for limiting the inward movement of said lever system.
- 5 10. In a coin-operated device, a coin-carrying member, a toggle, a connecting member fixed to said toggle, a contact member pivoted to said connecting member, a projection on one end of said

contact member, a stop member adjacent the opposite end of said contact member, said projection being adjusted to allow said contact member to extend beyond said stop member only when a coin of predetermined thickness, diameter and embossing is inserted in said coin-carrying member.

5

KARL GAMMEL.
